LIGHTED BOBBER FOR FISHLINES

William L. Kuhns, Girard, Ohio

Application May 13, 1939, Serial No. 273,446

2 Claims. (Cl. 43—17)

This invention relates to a lighted bobber for fishlines.

The principal object of this invention is the provision of a bobber for fishlines provided with an electric light so that the position of the bobber may be readily determined.

A further object of this invention is the provision of a lighted bobber for fishlines provided with switch means for lighting the light therein when a fish bites on the line to which the bobber is attached and means for setting the switch means in closed position so as to keep the bobber illuminated continually when desired.

A still further object of this invention is the provision of a lighted bobber provided with means for setting the switch means in open position so that the bobber may be used during the daytime without the light.

A still further object of this invention is the provision of a lighted bobber for fishlines formed of wood so as to have a certain definite buoyancy and provided with a removable top portion so that the bulb and battery therein can be conveniently replaced when necessary.

A still further object of this invention is the provision of a lighted bobber for fishlines that is impervious to water so that the same may be submerged and the light be visible and undiminished thereby.

The lighted bobber shown and described herein has been designed to provide an inexpensive, simple, yet practical lighted bobber for night fishing. It is well-known that many and various attempts have been made to provide lighted bobbers, the majority of which comprised complicated metal structures carrying complicated switch means, many of which have proven impractical under actual fishing conditions. The present invention therefore provides a lighted bobber formed of wood so as to be naturally buoyant and provided with an extremely simple switch mechanism, a portion of which supports the electric bulb just above the upper end of a battery positioned in a hollowed out portion of the bobber. The switch means has been provided with a simple adjustment so that it can be automatically actuated by a fish biting on a line attached thereto or it may be held in closed position thus keeping the bulb illuminated.

With the foregoing and other objects in view which will appear as the description proceeds, the invention resides in the combination and arrangement of parts and in the details of construction hereinafter described and claimed, it being understood that changes in the precise em-

bodiment of the invention herein disclosed, can be made within the scope of what is claimed without departing from the spirit of the invention.

The invention is illustrated in the accompanying drawing, wherein:

Figure 1 is a side elevation of the lighted bobber showing it in approximate floating position and showing portions of a fishline attached thereto.

Figure 2 is a cross sectional side elevation of the lighted bobber showing in detail the positioning of the battery and bulb therein and the switch means.

Figure 3 is an enlarged detail view of the bulb supporting bracket shown in Figure 2.

By referring to the drawing and Figure 1 in particular, it will be seen that the invention comprises a lighted bobber having a body portion 1 and a rounded top portion 2; a plurality of horizontal ports 3 in the rounded top 2 are equipped with suitable transparent material 4 so that light from a bulb therein may be seen. Positioned on the top of this rounded top portion 2 there is a coil spring 5 which serves as a convenient means for attaching a fishline 6 to the top of the bobber by wrapping the same about the coil spring 5. In Figure 1 the bobber is shown in approximate floating position, the surface of the water being indicated by the broken lines 7. It will be seen that the fishline 6 is preferably looped thru an eyelet 8 positioned on the lower portion of the body member 1 in order to provide sufficient slack between the eyelet 8 and an eyelet 9 formed on the end of a switch rod 10. It will be seen that the switch rod 10 enters the lower portion of the body member 1 thru a fitting 11 which is provided with a set screw 12 so that tension may be established against the switch rod 10 so as to hold it in any desired position thus enabling the bobber to be used in the daytime by setting the switch means in an open position and thus prevent the light therein from lighting.

By referring to Figure 2 of the drawing, it will be seen that a battery 13 is positioned in a hollowed out portion of the body member 1 by means of a tubular holder 14 which is attached at one side of the hollowed out portion of the body member 1 in such manner as to leave a passageway along its other side so that the switch rod 10 may pass upwardly alongside the tubular holder 14. In order that an electric bulb 15 may be positioned within the bobber, a bulb supporting bracket 16 is positioned between the battery 13 and the tubular holder 14 in such manner as to firmly wedge it therebetween and to establish electrical contact with

the side of the battery 13. This bulb supporting bracket 16 is provided with an opening 17 adapted to receive the threaded portion of the bulb 15 and is also provided with a smaller hole 18 thru which the upper end of the switch rod 10 is passed. In order that a downwardly motion of the switch rod 10 will result in springing the bulb supporting bracket 16 sufficiently to allow the bulb 15 to contact the battery 13, 5 a nut 19 is threadably positioned on the upper end of the switch rod 10 just above the opening in the bulb supporting bracket 16. This nut 19 permits the adjustment of the switch means after the battery has been replaced within the 10 device and the bulb supporting bracket 16 repositioned; it being understood that it might possibly be positioned in slight relation to the uppermost end of the battery 13 thus requiring some adjustment of the switch rod 10 in relation thereto. It will also be seen by referring 15 to Figure 2 of the drawing that a reflector 20 is positioned within the rounded top portion 2 of the bobber by means of a rivet 21 which also supports the coil spring 5. It is obvious that 20 a washer such as that shown at 22 in Figure 2 is preferably positioned between the body member 1 and the rounded top portion 2 so as to insure a water tight joint between these parts.

What I claim is:

30. 1. A fishline bobber comprising a hollow wooden body, a rounded top portion removably positioned on said body, a plurality of openings in said top portion, transparent material positioned in the said openings in a water tight manner, a tubular battery holder positioned in the said hollow wooden body, an L-shaped bracket, one end of which is positioned between the said tubular battery holder and a battery positioned therein so as to contact the side of the said battery, an opening in the other end of the 35 said L-shaped bracket adapted to receive an electric bulb and hold the same just above the upper end of the said battery, a rod movably positioned in the hollow wooden body, the upper end of which extends thru an opening in the said L-shaped bracket, a nut threaded on the upper end of the said rod and positioned immediately above the said L-shaped bracket, the lower end of the said rod extending out of the 40 said wooden body at its lower end thru a suitable gland, a set screw positioned in the said gland and adapted to exert pressure against the said rod so that the same may be held stationary in relation to the gland or permitted to move in relation to the gland, an eyelet formed on the bottom of the said rod to provide attachment means for a fishline so that jerks upon the fishline will result in the vertical movement of the said rod and a vertical movement of the bulb supporting portion of the L-shaped bracket so as to bring the said bulb into contact with the 45 said battery.

said wooden body at its lower end thru a suitable gland, a set screw positioned in the said gland and adapted to exert pressure against the said rod so that the same may be held stationary in relation to the gland or permitted to move in relation to the gland, an eyelet formed on the bottom of the said rod to provide attachment means for a fishline so that jerks upon the fishline will result in the vertical movement of the said rod and a vertical movement of the bulb supporting portion of the L-shaped bracket so as to bring the said bulb into contact with the said battery.

2. A fishline bobber comprising a hollow wooden body, a rounded top portion removably positioned on said body, a plurality of openings in said top portion, transparent material positioned in the said openings in a water tight manner, a reflector positioned in the said rounded top portion, a tubular battery holder positioned in the 15 said hollow wooden body, an L-shaped bracket one end of which is positioned between the said tubular battery holder and a battery positioned therein so as to contact the side of the said battery, an opening in the other end of the 20 said L-shaped bracket adapted to receive an electric bulb and hold the same just above the upper end of the said battery, a rod movably positioned in the hollow wooden body, the upper end of which extends thru an opening in the 25 said L-shaped bracket, a nut threaded on the upper end of the said rod and positioned immediately above the said L-shaped bracket, the lower end of the said rod extending out of the 30 said wooden body at its lower end thru a suitable gland, a set screw positioned in the said gland and adapted to exert pressure against the said rod so that the same may be held stationary in relation to the gland or permitted to move in relation to the gland, an eyelet formed on the bottom of the said rod to provide attachment 35 means for a fishline so that jerks upon the fishline will result in the vertical movement of the said rod and a vertical movement of the bulb supporting portion of the L-shaped bracket so as to bring the said bulb into contact with the 40 said battery.

WILLIAM L. KUHNS.
